UNITED STATES PATENT OFFICE

153,668

DESIGN FOR A VANITY TRAY FOR BATHTUB USE

Clara Mauriece Craighead, San Francisco, Calif.

Application January 11, 1947, Serial No. 136,097

Term of patent 7 years

(Cl. D86—10)

To all whom it may concern:

Be it known that I, Clara Mauriece Craighead, a citizen of the United States, residing at 531 Cabrillo Street, San Francisco, in the county of San Francisco and State of California, have invented a new, original, and ornamental Design for a Vanity Tray for Bathtub Use, of which the following is a specification, reference being had to the accompanying drawing, forming part thereof.

Fig. 1 is a perspective view of the vanity tray for bathtub use showing my new design in a closed position.

Fig. 2 is a perspective view of said tray in an open position.

Fig. 3 is a side elevational view of said tray in the closed position.

Fig. 4 is a top plan view of said tray in the closed position.

Fig. 5 is a front elevation of said tray in the closed position.

I claim:

The ornamental design for a vanity tray, for bathtub use, as shown.

CLARA MAURIECE CRAIGHEAD.
